FIG. 2.

M. F. ALLEN, INVENTOR.

BY Chamond Co.

FIG. 3.

UNITED STATES PATENT OFFICE

130,147

DESIGN FOR A MOTORCYCLE BAG

Maurice F. Allen, Elgin, Ill.

Application August 20, 1941, Serial No. 102,973

Term of patent 7 years

To all whom it may concern:

Be it known that I, Maurice F. Allen, a citizen of the United States, residing at Elgin, in the county of Kane and State of Illinois, have invented a new, original, and ornamental Design for a Motorcycle Bag, of which the following is a specification, reference being had to the accompanying drawing, forming part thereof.

I claim:

The ornamental design for a motorcycle bag, as shown.

MAURICE F. ALLEN.
